[57] CLAIM

The ornamental design for a vending machine for beverages or the like, as shown and described.

DESCRIPTION

FIG. 1 is a front perspective view of a vending machine for beverages or the like showing our new design; FIG. 2 is a right side elevational view thereof, the left side being a mirror image thereof;

FIG. 3 is a front perspective view of a second embodiment of that shown in FIG. 1;

FIG. 4 is a right side elevational view thereof, the left side being a mirror image thereof;

FIG. 5 is a front perspective view of a third embodiment of that shown in FIG. 1;

FIG. 6 is a right side elevational view thereof, the left side being a mirror image thereof;

FIG. 7 is a front perspective view of a fourth embodiment of that shown in FIG. 1; and

FIG. 8 is a right side elevational view thereof, the left side being a mirror image thereof.

FIG. 2
